US00D874536S

(12) **United States Design Patent** (10) **Patent No.:** **US D874,536 S**
(45) **Date of Patent:** **** Feb. 4, 2020**

(54) **SURVEILLANCE CAMERA**

(71) Applicant: **Hanwha Techwin Co., Ltd.**,
Seongnam-si (KR)

(72) Inventors: **Mun Jun Park**, Seongnam-si (KR);
Joo Young Shin, Seongnam-si (KR)

(73) Assignee: **HANWHA TECHWIN CO., LTD.**,
Seongnam-si (KR)

(**) Term: **15 Years**

(21) Appl. No.: **29/655,430**

(22) Filed: **Jul. 3, 2018**

(30) **Foreign Application Priority Data**

Jan. 3, 2018 (KR) 30-2018-0000420

(51) **LOC (12) Cl.** **16-01**

(57) **CLAIM**

The ornamental design for a surveillance camera, as shown and described.

DESCRIPTION

FIG. 1 is a front perspective view of a surveillance camera showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the surveillance camera that form no part of the claimed

(Continued)

design. The dot-dash broken lines shown in the drawings depict the boundaries of the claimed design and form no part of the claimed design.

1 Claim, 6 Drawing Sheets
